HUMIDIFIER

Filed Nov. 18, 1925

UNITED STATES PATENT OFFICE

THOMAS HILTON IRELAND, OF ROCKVILLE CENTER, NEW YORK

HUMIDIFIER

Application filed November 18, 1925. Serial No. 69,809.

This invention pertains to humidifiers for humidifying systems, such as those disclosed for instance, in my Patent No. 1,575,839 dated March 9, 1926, and is an improvement upon the apparatus therein described. While the principles thereof may be employed in various relationships, they have been embodied, for illustrative purposes, in a humidifier suitable for connection in or to an ordinary type of house heating system.

One of the objects of my invention, is to provide a humidifier which may be readily installed and connected in the supply line of the usual steam or hot water radiator or hot air register and one which may be manufactured and sold as a unit for installation with the installation of the usual heating system or for connection in heating systems already installed.

Another object of the invention is to provide a humidifier which will be entirely automatic in operation and one adapted to operate when the heating system is in operation and to remain idle when the heating system is idle.

Other objects include novel features of construction whereby the aforementioned objects may be attained and whereby the humidifier may be connected in the line supplying the radiator or the like at either end of the radiator regardless of the position of the radiator or the like in the room.

Still further objects of my invention should be readily appreciated after perusal of the description and claims and from inspection of the drawing in which:

Fig. 1 is a side elevation of my improved apparatus shown installed in connection with a radiator and a heated medium supply line thereto.

Fig. 2 is a side elevation partly in section showing one preferred form of the invention on a larger scale than that of Fig. 1 and

Fig. 3 is an end elevation looking at the right hand end of Fig. 2.

In Fig. 1 the usual steam or hot water radiator 2 has been shown connected through the valve 3 and line 4 with a main steam or hot water line 5, but it will be readily appreciated and understood that the connections

may be made in any other suitable manner and in the manner shown in my above noted patent when used in connection with a hot air heating system. I place the humidifier, generally designated 6, in the line 4, and preferably below the floor 5' in order that air circulation through the humidifier may be amplified by means of heat transferred from the radiator.

The humidifier 6 is preferably composed of two parts, an upper 7 and a lower portion 8. The lower portion 8 is formed substantially as shown in Figs. 2 and 3 to provide a water receiving reservoir 9 and a steam or hot water conduit or chamber 11 having no connection with the water chamber or reservoir 9, except that it may be integrally cast or otherwise formed therewith. The conduit or chamber 11 is provided with outwardly projecting portions 12 at its ends, which portions are tapped whereby they may receive the threaded ends of the line 4 and be connected therein. The water reservoir portion is preferably provided with oppositely disposed lugs 13 and 14, each cored and tapped to receive a pipe 15 for a purpose to be hereinafter described, and with spaced lugs 16 adapted to be connected with similar lugs 17 formed on the upper or cover portion 7 by means of bolts, lag screws or the like 18.

The top or cover portion 7 may be formed from sheet metal or from cast metal to provide a hollow inverted trough member to be superimposed upon the portion 8 and for tight connection therewith. The ends of the cover 7 are closed except for an outwardly projecting portion 19 forming a circular opening or the like telescopingly connecting with a vent pipe 20 and through which humidified air may pass from the humidifying chamber provided between the cover 7 and the lower portion 8, and except for a similarly projecting portion 21 providing a second opening to the interior whereby cool air may be supplied to the tank. A baffle plate 22 integral with or secured to the cover 7 extends across or substantially across the interior thereof adjacent the cool air supply end. This baffle extends downwardly from the top to the line of the bottom of the open-

ing in projection 21. Arrows indicate the air flow. The portion 21 likewise to the portion 19, is adapted to telescopically receive a cool air supply pipe 25 for a purpose which will hereinafter appear.

5 A float chamber 26 containing any suitable float mechanism, generally designated 27 for controlling a valve 28 operative to open and close the end of the delivery pipe 29 from 10 any suitable source of water supply, is provided with similarly placed tapped openings 31 and 32 whereby it may be connected to either of the tapped lug connections 13 and 14 by means of the pipe 15. The float chamber is also provided with an overflow pipe 33 adapted to be connected to it as shown at 34 or to the opposite side of the float chamber as shown at 35. Plugs 36, 37 and 38 are employed to close the unused openings 15 in the water reservoir and the float chamber. By constructing the float chamber and the water reservoir in this manner, I am enabled to dispose the float chamber on either side of the water reservoir and the humidifier 20 in the line of the heating system regardless of whether or not the line enters from the right or left hand end of the radiator, if the radiator is disposed close to the wall, as will be apparent. It will only be necessary 25 to transpose the pipe and plug connections from one side of the float chamber to the other to adapt it for transposition to the opposite side of the water reservoir.

The air intake pipe 25 extending through 30 the floor 5', preferably communicates with the interior of the room at or near the floor, although it may be placed in another room or carried to any source of supply of relatively cool air. The moist air vent or delivery pipe 20 preferably extends upwardly 35 through the floor and for a considerable distance in close proximity to the radiator or other heat distributor 2 so as to be heated thereby. The water in the tank is heated by 40 the heat supply pipe 4 and the heat from the radiator causes an upflow of air in the pipe 20 while at the same time the colder air along the floor flows through the pipe 25 into the tank 6 into close proximity to 45 the water therein and circulation is established whenever the radiator or other heat distributor is in operation.

In operation, the float mechanism is adapted to automatically open up the water supply pipe 29 to supply and maintain a sufficient quantity of water in the reservoir and float chamber. The float having been set to close the valve at a predetermined water level, the valve is closed by the float when that level 50 is reached. Should any excess water flow into the float chamber or the valve become stuck or any similar accident occur, the overflow pipe 33 will carry such excess water off. Water flowing from the float chamber 55 through the pipe connection 15 into the reser-

voir surrounds a substantial portion of the steam, hot water, or other heating medium conduit 11 and maintains heat absorbing contact with the walls thereof. The heated medium passing through the conduit serves gradually to vaporize the water in the humidifier reservoir.

70 In order to maintain circulation through the vapor chamber inside the reservoir and cover above the surface of the water in the reservoir, the humidifier is placed with the outlet 20 closely adjacent the radiator preferably between adjacent sections thereof as shown, in order that hot air rising therefrom will aid in inducing a flow of air 75 through the humidifier. Air entering the humidifier through the inlet is carried down into intimate contact with the surface of the water and absorbs water vapor therefrom, passes on through the humidifying chamber 80 and the outlet from the chamber to the vent 20. Circulation of air through the humidifier is primarily induced through the arrangement of the humidifier whereby air, entering the humidifier through pipe 25, being relatively cooler than air within the humidifier, forces the humidified and warmer air out. The draft through the humidifier is augmented by placing the outlet or vent pipe 20 adjacent or between the section of 85 the radiator as aforesaid.

90 While I have shown and described a preferred form of the invention and have set forth several uses to which it may be put, the invention in its broader sense is susceptible 100 of many variations and modifications, both in structure and mode of operation without departure from the spirit thereof or the scope of the appended claims.

95 I claim:

1. In a humidifier adapted to be disposed beneath the floor of a room, means providing a water reservoir of greater length than width, a chamber below said reservoir having a wall in common therewith and said chamber adapted to be connected in a heated medium carrying pipe line with the longitudinal axis of the reservoir parallel to the axis of the pipe line, a cover for said reservoir, said cover having two openings, one in each end, for circulation of air therethrough and across the water in said reservoir, and means whereby air pipes leading to and from a room to be humidified may be connected to said cover at said openings.

110 2. The invention according to claim 1, wherein further, water supplying means are provided below the floor for the reservoir, and heating medium controlling means arranged above the floor for controlling the 115 heating medium supplied to the chamber.

120 In witness of the foregoing I affix my signature.
